UNITED STATES PATENT OFFICE.

FRANK P. WISEBURN, OF BROOKLYN, AND LOUIS BUHLE, OF WOODHAVEN, NEW YORK, ASSIGNORS TO PATENT TOBACCO SAMPLE BINDER COMPANY, OF NEW YORK, N. Y.

BUNDLING APPARATUS.

SPECIFICATION forming part of Letters Patent No. 774,226, dated November 8, 1904.
Application filed July 2, 1904. Serial No. 215,117. (No model.)

To all whom it may concern:

Be it known that we, FRANK P. WISEBURN, residing in the city of New York, borough of Brooklyn, in the county of Kings, and LOUIS BUHLE, residing at Woodhaven, in the county of Queens, State of New York, have invented certain new and useful Improvements in Bundling Apparatus, of which the following is a specification, sufficient to enable others skilled in the art to which the invention appertains to make and use the same.

Our invention relates to means for securing samples of tobacco, as set forth in our Letters Patent No. 677,488, dated July 2, 1901, and is an improvement on the form of apparatus disclosed in our Letters Patent No. 734,488, dated July 21, 1902, the object being to facilitate and quicken the operation of applying the binder.

The invention consists in the special construction and arrangement of parts herein described and claimed specifically.

In the accompanying drawings, Figure 1 is a plan of our improved binding apparatus; Fig. 2, a front elevation of the same; Fig. 3, a side elevation; Fig. 4, a sectional elevation upon plane of line 4-4, Fig. 1; Fig. 5, a similar view showing the parts in a different position. Fig. 6 is a sectional elevation of the actuating-lever.

A is the table or bed-plate of the apparatus, formed for attachment to any suitable support and provided with the downwardly-projecting flanges a a' , upon and between which are mounted the rock-shafts c c' , to which are secured the segmental gears d d' , which mesh, each having an arm d^2 d^3 formed integral therewith, upon which arms are mounted the eccentric clamps e e' , provided with the handles e^2 e^3 , the clamping devices thus formed being the equivalent of and operating in the same manner as the eccentric clamp shown and described in our Letters Patent No. 724,488, hereinbefore referred to.

The table A is formed with the lateral slots or recesses a^2 a^3 to admit of the passage of the arms d^2 d^3 .

R is a ratchet-wheel rigidly secured to the

rock-shaft c' and engaging with a spring-pawl P, mounted upon the front of the flange a' , 50 the pawl P being preferably formed with a handle p or equivalent means for facilitating the disengagement of said pawl and ratchet-wheel when desired, as hereinafter set forth.

L is a hand-lever mounted loosely upon the shaft c' and provided with an auxiliary spring latch-lever m , pivotally secured thereto and formed with the ratchet-tooth m' for engagement with the teeth of the ratchet-wheel R, this engagement being maintained normally 60 and automatically by the spring m^2 .

The operation is as follows: The pawl P being temporarily disengaged from the ratchet-wheel R, the actuating-lever L is raised, thereby by reason of the engagement with the tooth 65 m' of the ratchet-wheel R rocking the shafts c c' so as to bring their arms d^2 d^3 into the slots a^2 a^3 and into the desired relation with the central portion of the table a^4 , upon which the hanks of tobacco forming the sample S 70 are placed, resting upon the binding-tape B, which has already been placed in position, the pawl P having in the meantime been released, so as to engage automatically the ratchet-wheel R and prevent the rotation of 75 the latter in one direction—namely, the right, as shown in the drawings. The ends of the binding-tape being now secured by the eccentrics e e' , the depression of the actuating-lever L draws the band B taut around the sample S, 80 the pawl P preventing slip or retractile movement. If it is desired to raise the lever L in order to conveniently rotate the ratchet-wheel R still further, the pawl-arm m is depressed against the resistance of the spring 85 m^2 , thereby releasing the tooth m' from the ratchet-wheel, the release of the pawl-arm m allowing the spring m^2 to return the tooth m' into engagement with the ratchet-wheel R at the desired elevation.

It is obvious that, if preferred, the actuating-lever L may be secured directly to the rock-shaft c' or ratchet-wheel R in cases in which the extent of motion imparted to the tightening-arms d^2 d^3 by a single downward stroke 95 of the lever L would be sufficient to take up

and draw taut the binder B around the sample S, so that we do not confine ourselves strictly to the use of the spring-lever m and pawl m' and which are designed mainly for convenience in that two or more short strokes of the lever may be resorted to in tightening the band, if desired.

What we claim as our invention, and desire to secure by Letters Patent, is—

- 10 1. In binding apparatus of the character designated, the combination of a supporting-table, two meshing segmental gears mounted under said table and each provided with a tightening-arm formed integral therewith, band-clamping devices on each of said tightening-arms and means for rocking said segmental gears, for the purpose set forth.
- 15 2. In binding apparatus of the character designated, the combination of a supporting-table, two meshing segmental gears mounted under said table and each provided with a tightening-arm formed integral therewith, band-clamping devices on each of said tightening-arms, means for rocking said segmental gears, and means for preventing the retractile movement of the said segmental gears, for the purpose set forth.
- 20 3. In bundling apparatus of the character designated, the combination of a supporting-table, two meshing segmental gears mounted under said table and each provided with a tightening-arm formed integral therewith, band-clamping devices on each of said tightening-arms, a ratchet-wheel integrally connected with one of said segmental gears, a hand-lever for actuating said ratchet-wheel, and means for preventing the retractile movement of the said ratchet-wheel, for the purpose set forth.
- 25 4. In bundling apparatus of the character designated, the combination of a supporting-table, two meshing segmental gears mounted under said table and each provided with a tightening-arm formed integral therewith,

band-clamping devices on each of said tightening-arms, a ratchet-wheel integrally connected with one of said segmental gears, a hand-lever mounted axially with relation to the ratchet-wheel and provided with a spring-pawl for engagement therewith, and a spring-pawl pivotally connected to a stationary part of the device, and arranged to engage with said ratchet for the purpose and substantially in the manner set forth.

5. In bundling apparatus, of the character designated, the combination of a supporting-table, A, formed with the projecting flanges a, a' , and lateral recesses a^2, a^3 , the rock-shafts c, c' , segmental gears d, d' , secured to said rock-shafts and having the tightening-arms d^2, d^3 , formed integral therewith, the band-clamping devices e, e' , mounted on said tightening-arms, the ratchet R secured to the shaft c' , the spring-pawl P, pivotally secured to the flange a' , and arranged to engage the ratchet-wheel R, and the actuating-lever L, arranged to rock the shaft c' , substantially in the manner and for the purpose set forth.

6. In bundling apparatus of the character designated, the combination of a supporting-table A, formed with the projecting flanges a, a' , and lateral recesses a^2, a^3 , the rock-shafts c, c' , segmental gears d, d' , secured to said rock-shafts and having the tightening-arms d^2, d^3 , formed integral therewith, the band-clamping devices e, e' , mounted on said tightening-arms, the ratchet R, secured to the shaft c' , the spring-pawl P, pivotally secured to the flange a' , and arranged to engage the ratchet-wheel R, and the actuating-lever L, mounted loosely upon the shaft c' , and provided with the engaging tooth m' , arm m , and spring m^2 , for the purpose set forth.

FRANK P. WISEBURN.
